Primary Examiner — Keli L Hill*Assistant Examiner* — Harold E Blackwell, II(74) *Attorney, Agent, or Firm* — Alston & Bird LLP**(57) CLAIM**

I claim the ornamental design for a support bracket, as shown and described.

DESCRIPTION

FIG. 1 is a top perspective view of a support bracket showing the new design;

FIG. 2 is a front elevation view of the support bracket of FIG. 1;

FIG. 3 is a rear elevation view of the support bracket of FIG. 1;

FIG. 4 is a left side elevation view of the support bracket of FIG. 1;

FIG. 5 is a right side elevation view of the support bracket of FIG. 1;

FIG. 6 is a top plan view of the support bracket of FIG. 1;

FIG. 7 is a bottom plan view of the support bracket of FIG. 1; and,

FIG. 8 is a bottom perspective view of the support bracket of FIG. 1.

The broken lines immediately adjacent shaded areas represent bounds of the claimed design, while all other broken lines are directed to environmental or unclaimed features. None of the illustrated broken lines form any part of the claimed design.
